United States Patent Office.

EDWIN J. TOOF, OF FORT MADISON, IOWA.

Letters Patent No. 75,317, dated March 10, 1868.

IMPROVEMENT IN LAMP-EXTINGUISHERS.

The Schedule referred to in these Letters Patent and making part of the same.

TO ALL WHOM IT MAY CONCERN:

Be it known that I, EDWIN J. TOOF, of Fort Madison, in the county of Lee, and State of Iowa, have invented a new and useful Improvement in Lamp-Burners; and I do hereby declare and make known that the following is a full, clear, and exact description of the same, reference being had to the accompanying drawings, and the letters and figures marked thereon, which form part of this specification.

My said invention relates to that class of burners in which the cone is hinged to the burner, and in which an extinguisher or cover to close the wick-tube is used; and it consists in an arrangement whereby the extinguisher may be removed from the wick-tube preparatory to lighting the lamp by the act of opening or removing the cone for that purpose, said extinguisher being provided with a suitable detent to retain it in place when the cone is replaced.

It further consists in a novel arrangement for closing or applying said extinguisher either by hand or by means of the shaft operating the wick-regulator, as hereinafter described.

And it further consists in a novel arrangement, hereinafter described, for forming a stop to the hinge of the cone, and also for raising and retaining the tube-cover in the proper position while the lamp is burning.

To enable those skilled in the art to understand how to construct and use my invention, I will describe the same with particularity, making reference in so doing to the aforesaid drawings, in which—

Figure 1 is a plan or top view of my said invention.

Figure 2 is a vertical central section, showing the extinguisher applied upon the wick-tube; and

Figure 3 is a similar section, showing the extinguisher thrown back and secured by the detent, the dotted lines representing the position of the parts when the cone is thrown back to light the lamp.

Similar letters of reference in the several figures denote the same parts of my invention.

A represents the wick-tube, and B the cover or extinguisher, which is provided with an arm, C, hinged or jointed to the cone D at α , on that side of the cone where it is hinged to the burner at β . To the under side of the arm C is jointed, in any suitable manner, as seen at α , and at such a point as to allow the cover B to pass properly over the tube when the cone is being closed, an arm, E, extending to the base of the burner, and of such length that its lower end, d , which may be straight, or may be bent to one side, rests upon a suitable support when placed in the proper position, and thus keeps the cover B away from the wick-tube, as hereinafter described.

When the end is bent it can pass out through a slot, b , in the case of the burner, to be operated as herein-after described.

There is a short lever, e , having its fulcrum in a slot in the side of the cap G, one end resting against the arm E and the other extending into the cap, so as to be operated upon as herein-after described.

This lever e is necessary only when it is desired to close the extinguisher or cover B upon the tube, by means of the wick-regulating shaft, as herein-after described, and the bend d upon the foot of the arm E is unnecessary, and need not project through the casing, only when it is desired to enable the operator to close the cover B by means of said bend or finger d ; or, instead of the lever e , an arm may be attached to the arm E, so as to operate to produce the same result.

Upon the lower side of the arm C, and near that end which is jointed to the cone, is formed a projection, m , which serves as a stop, acting against the side of the cone, to prevent the arm C from folding down too far when the cone is thrown back. A projection, F, is formed upon the interior of the casing, either by extending the plate of the hinge inward or otherwise, against which the arm E presses when the cone is being raised, thus throwing the foot of the arm E in upon its rest or support, as herein-after described.

Upon the arm E a stop or shoulder is formed, which comes up against the lower side of the projection F, just when the cone is opened back as far as desired, and thus, in connection with the projection m aforesaid, forms a stop to the hinge of the cone as desired.

H represents a shaft passing through the burner at right angles with the longer diameter of the wick-tube, at a sufficient distance therefrom to allow the parts of the regulating-slide L, clasping the edges of the tube, to retain the slide L thereupon to move between, or the slide may have suitable bearings upon the face of the tube to retain it in place, if desired, when the shaft H may lie close against the tube if desired. The said shaft H is

provided with an arm, I, having a U-shaped end, which enters a loop, l, upon the regulating-slide L, so that the rotation of the said shaft will regulate the wick, moving said toothed slide up and down as desired, a spring, S, being used, if desired, to hold the regulator up to the wick, which will, however, permit the teeth to be withdrawn and turned down to give additional elevation to the wick when desired. The said shaft H is also provided with another arm, J, upon the opposite side of the wick-tube, at such a point as to lie above the lever e, operating on the arm E connected with the extinguisher.

When this improvement is applied to burners having the ratchet-wheel wick-regulator, the shaft itself, or the longitudinal play which the shaft has or should have, may be made available, either directly or indirectly, by means of an arm or lever operating by or in combination with the shaft, as shown in model, when it is being rotated, to remove the supporting-arm E from its rest, and cause the cap B to fall upon the top of the wick-tube as desired.

Having described the nature and construction of my invention, I will now describe the mode of its operation.

In fig. 2 the parts are shown in the position assumed when the lamp is not lighted or in use. When it is desired to light the lamp, the cone D is thrown back upon its hinge at h into the position indicated by the dotted lines in fig. 3, when the arm E rests against a stop or rest, F, arranged within the case of the burner, as shown, and hereinbefore mentioned, and thus prevents the further backward movement of the cone upon its hinge, enabling the ordinary hinge to be used at h. The wick is then turned up in the ordinary manner, and the lamp is lighted. At the same time that the movement of the cone causes the arm E to press against the stop F, as aforesaid, it draws the arm upwards slightly, so that the pressure of the stop F upon the arm E throws the foot of the arm E into the slot b, and over its support, upon which it rests when the cone is closed, so as to hold the cover B away from the wick-tube, as desired, when the lamp is in use, as indicated by the full lines in fig. 3.

When it is desired to extinguish the lamp the shaft H is revolved in the direction to turn down the wick in the tube, which extinguishes the light, and at the same time the arm J, pressing down upon the lever e, applies the cap B upon the top of the tube, the elastic detent d yielding to the pressure and resuming its former position.

When the operation of applying the extinguisher is to be performed, as above described, it is unnecessary to have the finger d project through the exterior case, but it may so project if desired. When the finger d does project through the case, and the wick-regulating device is not arranged so as to operate in closing the extinguisher, the wick may be turned down in the ordinary way, and the cap or extinguisher be applied by drawing the finger d from its support in the slot b, and allowing it to resume the position shown in fig. 2. The office of the arm E being mainly to support the cover B while the lamp is in use, the closing of the cover upon the tube is effected by displacing the foot of the said arm E from its support, so as to allow the cover to drop upon the tube, which displacement may be effected by the means herein described, or in any other suitable manner.

It may be observed that where the cones are hinged to the burners so as to swing horizontally from over the wick-tube, the arrangement of the arms of the extinguisher may be readily modified, so that such movement of the cone shall remove the extinguisher from the wick-tube, and substantially the same means as herein described may be used to replace it.

Having described the construction and operation of my invention, I will now specify what I claim, and desire to secure by Letters Patent.

1. I claim so combining a hinged cone, D, extinguisher or cap B, and a connecting-arm C, or its equivalent, that the opening of the cone will remove the extinguisher from the wick-tube, substantially as herein specified and set forth.

2. In combination with said extinguisher, cone, and connecting-arm, I claim the arrangement of a suitable support E, to retain the extinguisher away from the wick-tube when the cone is closed, substantially as herein specified and described.

3. I claim the combination of a finger, d, operating through a slot in the external case of the burner, in combination with the arm E, connecting-arm C, extinguisher B, and cone D, substantially in the manner and for the purposes set forth.

4. I claim, in combination with the cone D, hinged as described, and the arm E, arranged in connection therewith substantially as described, a stop or rest, F, upon the case of the burner, arranged so as to sustain the cone in place, and prevent it swinging over upon its hinge, substantially in the manner described.

5. I claim, in combination with the extinguisher B, cone D, connecting-arm C, arm E, provided with a suitable rest and a lever, e, the shaft H and arm J, arranged to operate substantially in the manner herein set forth.

EDWIN J. TOOF.
